UNITED STATES PATENT OFFICE

CYRUS HANKINS, OF WASHINGTON, DISTRICT OF COLUMBIA

BRAKE RIGGING FOR RAILWAY CARS

Application filed March 26, 1931. Serial No. 525,531.

My invention relates to railway cars and more particularly to improvements in the brake rigging thereof.

A principal object of the invention is to provide means for connecting the upper end of the dead lever of the brake rigging to the underframe of the car in such manner that the lever may be free to move angularly with respect to the longitudinal axis of the underframe in substantially all directions to compensate for relative movement between the underframe and the car truck.

A primary feature of the invention consists in providing means for flexibly connecting the dead lever to the underframe of the car involving means pivotally connected at one end to the dead lever and having at the other end ball and socket connection with a bracket secured to the underframe.

Another feature of the invention consists in rigidly securing a bracket to the underframe of the car and in movably connecting the upper end of the dead lever to the bracket, a portion of said connecting means and the bracket having spherically curved cooperating portions.

A further feature of the invention consists in providing the underframe of the car with a bracket and in connecting the upper end of the dead lever to the bracket by means involving a member provided with a spherically curved portion, the bracket having an opening of greater width than the curved portion through which said member is adapted to extend and means disposed within the opening affording a seat for the curved portion of the member.

A still further feature of the invention consists in providing means for connecting the upper end of the dead lever to the underframe of the car involving a bracket rigid with the underframe and a member movably associated therewith, said bracket having an aperture through which said member extends and the latter being provided with a curved portion of greater width than said aperture, means being disposed within the aperture of the bracket defining an opening of less width than the curved portion of the member and affording a seat therefor.

Other and more specific features of the invention residing in advantageous forms, combinations and relations of parts will hereinafter appear and be pointed out in the claims.

In the drawing illustrating a preferred embodiment of the invention:

Figure 1 is a fragmentary, vertical sectional view of a railway car showing my invention applied thereto.

Figure 2 is a plan view, partly in section, of a portion of the construction illustrated in Figure 1.

Figure 3 is an enlarged view taken on line 3—3, Figure 1 showing the bracket of the dead lever connecting means in end elevation.

Figure 4 is a sectional view taken on line 4—4, Figure 3.

Figure 5 is an enlarged sectional view on line 5—5, Figure 1.

As is well known the conventional brake rigging for railway cars consists of a fluid pressure cylinder rigidly mounted on the underframe of the car and a system of connected rods and levers for transmitting force from the cylinder to the brake shoes mounted on brake beams and cooperable with the wheels of the car. The brake beams are pivotally connected to and actuated by the brake levers which as is well known are inclined at an angle of approximately forty degrees to the vertical. One of these brake levers, namely, the one to which the brake applying force is first transmitted from the brake cylinder, is termed the live lever while the other brake lever, namely the one anchored to some part of the car, is usually termed the dead lever. As the invention only relates to means for connecting or anchoring the dead lever to the car only this lever and adjacent portions of the brake rigging have been illustrated.

Referring more particularly to the drawing 1 indicates the dead lever and 2 the push rod which connects the lower ends of the dead and live levers. The brake beam which is actuated by the dead lever and is pivotally connected thereto by a pin 3 has been illus-

trated and is designated by the reference numeral 4.

The means for connecting the upper end of the dead lever to the car underframe comprises a tension connector involving two members 5 and 6, respectively. Member 5 may advantageously be of U-shape having arms 7 disposed in planes substantially parallel to the plane of normal operation of the dead lever and spaced a sufficient distance apart for receiving the upper end of the latter. The arms are connected to the dead lever by a pivot pin 8 whose axis is substantially perpendicular to the plane of normal operation of the lever and in order that the dead lever may be connected to member 5 in a plurality of positions of adjustment to take up slack in the brake rigging, the arms 7 are provided with a plurality of pairs of registering apertures 9, any pair of which is adapted to receive the connecting pin 8.

The other member 6 of the tension connector is movably associated with a bracket 10 which is preferably formed as an integral casting and is rigidly secured to the underframe of the car. One end of member 6 is provided with a ball portion 11 cooperable with the bracket, and the other end thereof is provided with a portion 12 interposed between and connected by a pin 13 to the arms 7 of the U-shaped member 5. Integrally formed with the portion 12 and projecting in opposite directions therefrom are lugs 14, one of which is adapted to be disposed in overlapping relation with the lower edge of one arm of the U-shaped member and the other one of which is adapted to be disposed in overlapping relation with the upper edge of the other arm thereof. It will thus be observed that members 5 and 6 are immovably connected, the pin 13 serving to prevent relative longitudinal movement and the lugs 14 together with the pin 13 serving to prevent relative angular movement. If desired, the end portions of the arms 7 adjacent the member 6 may be provided with a pair of registering apertures 15 in addition to the ones in which, as shown in Figure 1, the pin 13 is disposed to assist in taking up slack in the brake rigging. The distance between the centers of these apertures is preferably greater than the distance between the centers of apertures 9 so that a very fine degree of adjustment may be obtained.

The bracket 10 is provided with a top flange or plate portion 16 for attachment by rivets 17 to the bottom flange 18 of an adjacent center sill 19 of the car underframe. Extending downwardly from the flange 16 is a substantially vertical plate portion 20 which terminates in an enlarged circular portion 21 offset downwardly and outwardly from the flange. The bracket may advantageously be rigidified by flanges 22 and 23 which project from opposite sides of the plate

portion 20. The flange 22 tapers downwardly from adjacent the outer edge of the top flange 16 to adjacent the upper part of the circular portion 21 while the flange 23 tapers downwardly from adjacent the inner edge of the top flange to the rear part of the circular portion.

The circular portion 21 is formed with an internal flange 24 which defines an opening of greater width than the ball portion 11 of the member 6 through which that member extends. Rigidly secured to the internal flange 24 are two, preferably semi-circular, members 25 respectively having portions 26 disposed within the opening defined by the flange 24. The members 25 define an opening of less width than the ball portion 11 and are formed with concave spherically curved portions affording a seat for the convex spherically curved portion of the member 6. Each of the members 25 is preferably secured to the bracket by only one rivet 27 so that they may be easily removed from the bracket. The purpose of providing the bracket with removable portions 25 is not only to permit replacement of those members but also to permit the member 6 to be associated or disassociated with the bracket. As pointed out the opening defined by the internal flange 24 is of greater width than the ball portion 11 so that when the semi-circular seat members 25 are removed by cutting or shearing the rivets 27, the ball portion 11 of member 6 may be withdrawn through the opening. It will, of course, be understood that if the end portion 12 of the member 6 is of such size that it can be pulled through the opening defined by the members 25 the latter need not be formed separately from the bracket.

By providing a tension connector having at one end pivotal connection to the dead lever and having at the other end ball and socket connection with the bracket, it will be appreciated that the dead lever is universally connected to the bracket and consequently may move angularly with respect to the longitudinal axis of the underframe in substantially all directions to compensate for relative movement between the car truck and car body.

I claim:

1. In a railway car brake rigging, the combination with the underframe of a car, of a dead lever, a bracket rigid with the underframe and having a recessed portion, and means movably connecting the upper end of the dead lever to the bracket, said means involving a member having a curved portion movably associated with the bracket, said bracket being provided with means disposed within said recess affording a seat for the curved portion of said member.

2. In a railway car brake rigging, the combination with the underframe of a car, of a dead lever, a bracket rigidly secured to the underframe, means for connecting the upper

- end of the dead lever to the bracket, said means involving a member movably associated with the bracket and provided with a spherically curved portion, said bracket having an opening of greater width than the said curved portion through which said member is adapted to extend, and means disposed within said opening affording a seat for the curved portion of said member.
3. In a railway car brake rigging, the combination with the underframe of a car, of a dead lever, a bracket rigidly secured to the underframe, means for connecting the upper end of the dead lever to the bracket, said means involving a member movably associated with the bracket and provided with a spherically curved portion, said bracket having an opening of greater width than the said curved portion through which said member is adapted to extend, and means disposed within said opening defining an opening of less width than said curved portion and affording a seat for the latter.
4. In a railway car brake rigging, the combination with the underframe of a car, of a dead lever, a bracket rigidly secured to the underframe, means for connecting the upper end of the dead lever to the bracket, said means involving a member movably associated with the bracket and provided with a spherically curved portion, said bracket having an opening of greater width than the said curved portion through which said member is adapted to extend, and a plurality of removable members secured to said bracket and respectively having portions disposed within the opening thereof defining an opening of less width than the said curved portion of the member, said removable members having curved portions affording a seat for the said curved portion.
5. In a railway car brake rigging, the combination with the underframe of a car, of a dead lever, a bracket rigidly secured to the underframe, means for connecting the upper end of the dead lever to the bracket, said means involving a member movably associated with the bracket and provided with a spherically curved portion, said bracket having an opening of greater width than the said curved portion through which said member is adapted to extend, and two semi-circular members secured to said bracket and respectively having portions disposed within the opening defining an opening of less width than said curved portion, said semi-circular members having curved portions affording a seat for the curved portion of said member.
6. In a railway car brake rigging, the combination with the underframe of a car, of a dead lever, a bracket rigid with the underframe and having a portion disposed below the latter provided with an opening, means for connecting the upper end of the dead lever to the bracket, said means involv-
- ing a member disposed within the opening of the bracket and having a spherically curved portion of less width than said opening, and removable means disposed within said opening affording a seat for the curved portion of said member.
7. In a railway car brake rigging, the combination with the underframe of a car, of a dead lever, a bracket rigid with the underframe and having a circular portion provided with an internal flange defining an opening, means for connecting the upper end of the dead lever to the bracket, said means involving a member extending through the opening of the bracket and provided with a spherically curved portion of less width than said opening, and means removably secured to said bracket and having portions disposed within the opening thereof defining an opening of less width than the curved portion of said member, said removable means affording a seat for the said curved portion.
8. In a railway car brake rigging, the combination with the underframe of a car, of a dead lever, a bracket rigid with the underframe having a top portion for attachment to the latter and a downwardly offset portion provided with an opening, said bracket being integrally formed with flanges connecting said top portion and said offset portion, means for movably connecting the upper end of the dead lever to the bracket, said means comprising a member extending through the opening of the bracket and provided with a curved portion of less width than said opening, and means secured to said bracket having portions respectively disposed within the opening of the latter defining an opening of less width than the said curved portion of said member, said last-named means affording a seat for the said curved portion.
9. In a railway car brake rigging, the combination with the underframe of a car, of a dead lever, a bracket rigidly secured to the underframe, and means movably connecting the upper end of the dead lever to the bracket, said means comprising a U-shaped member having spaced arms pivotally connected to the lever and a rigid member having ball and socket connection with said bracket, said rigid member being provided with a portion interposed between and connected to the arms of the U-shaped member.
10. In a railway car brake rigging, the combination with the underframe of a car, of a dead lever, a bracket rigid with the underframe, a U-shaped member having spaced arms pivotally connected to the upper end of the dead lever, and a rigid member having a portion interposed between and connected to the arms of said U-shaped member, said rigid member and bracket being respectively provided with spherically curved co-

operating portions, the portion of the rigid member interposed between the arms of said U-shaped member being provided with oppositely projecting lugs arranged in overlapping relation to the edges of said arms.

5 In testimony whereof I affix my signature.
